Primary Examiner — Mark A Goodwin*Assistant Examiner* — Adam C Mager(74) *Attorney, Agent, or Firm* — Taft Stettinius & Hollister LLP**CLAIM**

The ornamental design for a truck, as shown and described.

DESCRIPTION

FIG. 1 is a front, top, left side perspective view of a truck showing our new design;

FIG. 2 is a front, top, right side perspective view thereof;

FIG. 3 is a rear, top, left side perspective view thereof;

FIG. 4 is a rear, top, right side perspective view thereof;

FIG. 5 is a front elevational view thereof;

FIG. 6 is a rear elevational view thereof;

FIG. 7 is a left side elevational view thereof;

FIG. 8 is a right side elevational view thereof; and,

FIG. 9 is a top plan view thereof.

The broken lines in the drawings are for the purpose of illustrating portions of the truck and form no part of the claimed design.

1 Claim, 8 Drawing Sheets(56)
